UNITED STATES PATENT OFFICE.

CLYDE B. MOON, OF BURR OAK, KANSAS.

CURTAIN CARRIER FOR AUTOMOBILES.

Application filed August 1, 1925. Serial No. 47,536.

To all whom it may concern:

Be it known that I, CLYDE B. MOON, a citizen of the United States, residing at Burr Oak, in the county of Jewell and State of Kansas, have invented certain new and useful Improvements in Curtain Carriers for Automobiles, of which the following is a specification, reference being had to the accompanying drawings.

This invention relates to devices for supporting curtains within automobiles, and particularly to a device of this character in the nature of a reel upon which the curtains may be wound and thus conveniently and compactly carried, this application being a continuation in part of the application filed by me on the 2nd day of December, 1924, Serial #753,470, for curtain carriers.

The general object of the invention is to provide a device of this character which includes a carrier adapted to be supported upon one of the bows of the car top, and provide a reel mounted within the carrier and having means whereby curtains may be clasped upon the reel proper.

A further object is to provide a device of this character with means whereby the reel may be rotated to wind up the curtains, such means being so constructed that the reel may be readily withdrawn from the carrier when desired.

Other objects have to do with the details of construction and arrangement of parts as will appear more fully hereinafter.

My invention is illustrated in the accompanying drawing, wherein:

Figure 1 is a perspective view of a curtain carrier constructed in accordance with my invention and shown as supported upon a bow of a vehicle top;

Figure 2 is a longitudinal vertical sectional view through the curtain carrier;

Figure 3 is a vertical section through the curtain carrier and the support A;

Figure 4 is a perspective view of one of the slides;

Figure 5 is a perspective view of one of the springs carried by the slides;

Referring to this drawing, it will be seen that I have provided a carrier or holder for curtains which is designated 10 and which is preferably made of canvas, though other materials might be used. The body 10 is partially cylindrical and is attached at its ends to heads 11 which may be made of metal, leather or any other suitable ma-

terial. The canvas may be riveted to these heads. Preferably the canvas is riveted, punched or otherwise attached at its ends to these heads only around a portion of the circumference of the carrier or case 60 10 so that the upper portion of the case or carrier 10 is either entirely open or is simply protected by a cover or loose piece of canvas 12. This cover may be held closed and the carrier supported from the 65 bow A of a vehicle by means of straps or bands 13 which extend around and are preferably attached to the body 10, and each of these bands at one point is formed to provide a loop 14 by passing the band or 70 strap through a buckle 15 or by any other means of like character, the bow of the vehicle top passing through the loops 14 thus formed and the buckles 15 extending beneath the bow so as to hold the carrier 75 in place when the straps are released to open the flap 12 and remove the contents of the carrier.

I do not wish to be limited to the use of the specific buckle shown, as other means 80 might be used for this purpose forming a loop over the bow. The straps 13 are held in position to close the carrier by means of buckles 16 of ordinary character. Extending through openings in the heads 11 is a 85 shaft 17, this shaft being square in cross section or, if desired, being round in cross section or having any other cross sectional shape, though preferably square. Slidably mounted upon the winding shaft 17 are the 90 slides 18. Each slide is formed with an aperture 19, the aperture being square, if the shaft is square in cross section, by which the slide may shift longitudinally upon the winding shaft 17. This slide is illustrated 95 as rounded at the bottom but flat on top and being formed upon its inner surface with a vertically extending dove-tailed groove 20. Engaging in this dove-tailed recess is the angular end 21 of a leaf spring 100 22. Each leaf spring, therefore, extends downward from the top of the slide to a point in proximity to the face of the shaft, then extends longitudinally along the shaft, and then upward at the extremity, as at 23. 105 The slides, as before stated, may be moved longitudinally upon the shaft so as to accommodate curtains of different widths.

Mounted upon the extremities of the shaft and exteriorly of the heads 11 are the knobs 110 24 whereby the shaft may be rotated. These

may be of any desired character but I have illustrated the knobs as being formed with sockets for the reception of the ends of the shaft and being pinned to the shaft by the pin 25. When it is desired to remove the shaft 17 from within the carrier or holder 10, one of these pins 25 is removed with the corresponding knob 24 and then the shaft may be shifted longitudinally so that it will 10 be disposed entirely exteriorly to the casing or carrier 10. The carrier 10 being made of canvas is liable to sag at the middle and at the ends, particularly when there are no curtains rolled up within the carrier, and in 15 order to prevent this I preferably brace the carrier longitudinally by means of three or more braces 26 which may be made of metal, wood or any other suitable material.

Under some circumstances, a round rod or 20 shaft 17 may be used in place of the square shaft, in which case this round rod will be formed with a longitudinal keyway and the slides will be formed with a feather or key extending into this keyway.

25 In the operation of this device, when it is desired to roll up and house the automobile curtains, the slides may be separated, the curtains disposed upon the shaft 17, then the slides forced together, the upwardly turned 30 ends 23 of the springs permitting the springs to ride over the first layer of the curtain. The shaft is then rotated to wind the curtain up upon the shaft, and obviously after the first turn has been made the curtain will 35 thereafter lap over the springs 22 and this overlapping of the curtain upon these springs 22 will assist the springs in holding the first convolution of the curtain tightly to the shaft. Obviously, if more than one curtain 40 is to be rolled up upon the shaft, the first curtain is rolled up until the roll is nearly completed and the second curtain may be inserted between the layers of the first curtain and the rolling continued until the second curtain has been rolled in one or two 45 layers around the first curtain, which will then serve to hold the second curtain in place, and thus the rolling up may be continued until all of the curtains have been 50 rolled up in one compass in the carrier, where they are protected from dust or dirt, kept from being broken or otherwise injured, and yet may be had readily by the simple process of pulling the curtains out 55 one by one off of the shaft 17.

Under some circumstances the flexible cover 12 or flap may be omitted and the reel and curtains will then be supported on what might be termed a sort of cradle open at the 60 top. By releasing the buckles 16, the carrier will swing downward so that the curtains may be readily removed from the shaft. The device is very simple, compact, and will 65 keep the curtains, as before stated, from being broken, torn or otherwise injured.

I claim:—

1. A curtain carrier of the character described comprising an outer case having ends, the case having a body portion approximately semi-circular in cross section, 70 supporting means for the case whereby it may be supported from the bow of a vehicle top, a reel shaft passing through the ends of the case and rotatably supported therein, means on the extremities of the 75 shaft whereby the shaft may be rotated, and means mounted upon the shaft for engaging the margin of a curtain therewith, said means being adjustable longitudinally upon the shaft held for rotation independently 80 of the shaft.

2. A curtain carrier of the character described comprising an outer case having ends, the case having a body portion approximately semi-circular in cross section, 85 supporting means for the case whereby it may be supported from the bow of a vehicle top, a reel shaft passing through the ends of the case and rotatably supported therein, means on the extremities of the 90 shaft whereby the shaft may be rotated, and means mounted upon the shaft for engaging the margin of a curtain therewith, said means including two members, each longitudinally adjustable upon the shaft independently of the other and each held upon the shaft against rotation independently thereof and each adapted to engage over the margin of a curtain and hold it to the shaft.

3. A reel for curtains including a case, a shaft passing longitudinally through the case and being rotatably mounted on the ends thereof, slides mounted upon the shaft inward of the ends of the case and held upon the shaft against independent rotation, 105 means upon the extremities of the shaft whereby it may be rotated, and springs carried by said slides and extending toward each other and bearing upon the face of the shaft, the springs being adapted to engage the opposite margins of a curtain to hold the curtain to the shaft as the shaft is rotated.

4. A curtain carrier of the character described comprising an outer case having circular ends, the body of the case being approximately semi-circular, straps passing around the case and attached to the body thereof, said straps being formed each at one point with a loop adapted to embrace the bow of a vehicle top and said straps having means whereby they may be buckled to the case, a longitudinally extending shaft rotatably mounted on the ends of the case, knobs mounted upon the extremities of the shaft whereby the shaft may be rotated, and means mounted adjacent opposite ends of the shaft whereby a margin of a curtain may be held to the shaft, the two means being adjustable toward or from each other. 110

5. A carrying device for curtains comprising a case having ends, a shaft extending through the case, means upon the extremities of the shaft whereby it may be rotated, slides 5 mounted upon the shaft adjacent each end thereof and shiftable longitudinally upon the shaft but rotatable therewith and each slide having a vertical groove upon its inner face, and a leaf spring for each slide, each 10 spring being angularly bent at its dorsal end to extend into said groove and be supported thereby, each spring extending inward toward the shaft and then longitudinally along the shaft and then slightly outward 15 whereby to receive between it and the shaft the margins of a curtain.

6. A curtain carrier of the character described comprising an outer case having end members, straps fastening around the case and attached to the body thereof and each 20 formed at one point with a loop adapted to embrace the bow of a vehicle top and said straps having means whereby they may be buckled to the case, a longitudinal shaft rotatably mounted in the ends of the case and 25 projecting outward thereof whereby the shaft may be rotated and means mounted upon the shaft whereby the margin of the curtain may be held to the shaft.

In testimony whereof I hereunto affix my 30 signature.

CLYDE B. MOON.
